DESIGN FOR A BEVERAGE MIXER

Robert MacDougall, Rock Falls, Ill., assignor to Prince Castles Manufacturing Division, a partnership consisting of Earl S. Prince, Marion L.
Prince, E. H. Prince estate, and Robert
MacDougall

Application June 21, 1940, Serial No. 93,177

Term of patent 14 years

To all whom it may concern:

Be it known that I, Robert MacDougall, a citizen of the United States, residing at Rock Falls, in the county of Whiteside and State of Illinois,
have invented a new, original, and ornamental Design for a Beverage Mixer, of which the following is a specification, reference being had to the accompanying drawing, forming part thereof, in which a front perspective view is shown. The rear view is the same, except that the conventional snap switch, shown in the front perspective view, is not visible from the rear.

I claim:

The ornamental design for a beverage mixer,
as shown and described.
